(57) **ABSTRACT**

An electronic cigarette body, a vaporization device, and an electronic cigarette are provided. The electronic cigarette body includes a housing provided with a power supply. One end of the housing is configured to be connected to the vaporization device, and an airflow channel is provided in the housing. A heating portion and a heated portion in an airflow communication with the heating portion are provided in the airflow channel. One end of the vaporization device is provided with a mouthpiece and the other end of the vaporization device is configured to be connected to the electronic cigarette body. The electronic cigarette includes the electronic cigarette body and the vaporization device. The electronic cigarette body, the vaporization device, and the electronic cigarette provided in this application may enrich flavors of the vapor vaped by a user and improve the user's experience.

**ELECTRONIC CIGARETTE BODY,
VAPORIZATION DEVICE, AND
ELECTRONIC CIGARETTE**

**CROSS-REFERENCE TO RELATED
APPLICATION**

This application is a national stage application filed under 35 U.S.C. 371 of International Application No. PCT/CN2021/096347 filed May 27, 2021, which claims priority to China Patent Application No. 202022087361.8 filed Sep. 21, 2020. The entire disclosures of the above applications are incorporated herein by reference in their entirety.

TECHNICAL FIELD

This application relates to an electronic device, and specifically to an electronic cigarette body, a vaporization device, and an electronic cigarette.

BACKGROUND

In recent years, manufacturers start to produce a wide range of electronic cigarette products, including an e-liquid type electronic cigarette product that heats and atomizes a volatile solution to produce a vapor for a user to vape. E-liquid generally includes different flavors of fragrances, which can be atomized to produce different fragrances.

SUMMARY

This application provides an electronic cigarette body, a vaporization device, and an electronic cigarette to provide aroma of the electronic cigarette in a way that is different from the related art.

This application provides an electronic cigarette body. The electronic cigarette body includes a housing provided with a power supply. One end of the housing is configured to be connected to a vaporization device, and an airflow channel is provided in the housing. A heating portion and a heated portion in an airflow communication with the heating portion are provided in the airflow channel.

In an implementation, the heated portion is located at downstream of the heating portion in an airflow direction.

In an implementation, the electronic cigarette body further includes a temperature sensor, configured to measure a temperature of the heating portion.

In an implementation, the housing has a first part and a second part located at the one end, the second part being located between the first part and the one end; and the first part is configured to dispose the heating portion and the heated portion, and the second part is configured to be connected to the vaporization device.

In an implementation, a hollow base is provided in the first part, a hollow part of the hollow base including a heating region and a heated region, respectively configured to dispose the heating portion and the heated portion.

In an implementation, the heating region and the heated region are arranged in a direction toward the one end.

In an implementation, an electric connection terminal is further provided in the first part, the electric connection terminal being disposed between the base and an inner wall of the housing.

This application further provides a vaporization device. One end of the vaporization device is provided with a mouthpiece and the other end of the vaporization device is configured to be connected to the electronic cigarette body.

2

In an implementation, an end portion of the other end of the vaporization device is provided with a concave portion. The concave portion, used as a heated portion, is configured to be in communication with the heated portion of the electronic cigarette body and accommodate part of a flavor adjusting portion.

In an implementation, the concave portion is located at a central region of the end portion.

This application further provides an electronic cigarette. 10 The electronic cigarette includes the aforementioned electronic cigarette body and vaporization device.

In an implementation, the concave portion of the vaporization device is aligned with the heated portion of the electronic cigarette body in a depth direction of the concave portion.

The electronic cigarette body, the vaporization device, and the electronic cigarette provided in this application may enrich flavors of the vapor vaped by a user and improve the user's experience.

20

BRIEF DESCRIPTION OF THE DRAWINGS

The accompanying drawings are provided for further understanding of this application and constitute part of the specification, and explain this application together with the following specific implementations, but do not constitute a limitation to this application. In the accompanying drawings:

FIG. 1 is a schematic diagram of an electronic cigarette 30 according to some embodiments of this application.

FIG. 2 is a schematic diagram of a demonstrative combination of an electronic cigarette according to some embodiments of this application.

FIG. 3A, FIG. 3B, FIG. 3C, and FIG. 3D are schematic 35 exploded views of a vaporization device according to some embodiments of this application.

FIG. 4A, FIG. 4B, FIG. 4C, and FIG. 4D respectively are a section side view, a partial enlarged side view, a section front view, and a partial enlarged front view of an electronic 40 cigarette body according to some embodiments of this application.

FIG. 5 is a structural section view of an electronic cigarette according to some embodiments of this application.

45

DETAILED DESCRIPTION

The following disclosure provides many different embodiments or examples for implementing different features of the provided subject matter. The following describes particular examples of members and deployments. Certainly, these are merely examples and are not intended to be limitative. In this application, in the following descriptions, reference formed by the first feature above or on the second 50 feature may include an embodiment formed by direct contact between the first feature and the second feature, and may further include an embodiment in which an additional feature may be formed between the first feature and the second feature to enable the first feature and the second feature to be not in direct contact. In addition, in this application, reference numerals and/or letters may be repeated in examples. This repetition is for the purpose of simplification and clarity, and does not indicate a relationship between the described various embodiments and/or configurations.

The embodiments of this application are described in detail below. However, it should be understood that, this application provides many applicable concepts that can be

55

60

65

implemented in various particular cases. The described particular embodiments are only illustrative and do not limit the scope of this application.

FIG. 1 is a schematic diagram of an electronic cigarette 100 according to some embodiments of this application.

The electronic cigarette 100 includes a vaporization device 100A and an electronic cigarette body 100B. In some embodiments, the vaporization device 100A and the electronic cigarette body 100B may be designed as a unity. In some embodiments, the vaporization device 100A and the electronic cigarette body 100B may be designed as two separate members. In some embodiments, the vaporization device 100A may be designed to be removably combined with the electronic cigarette body 100B. In some embodiments, when the vaporization device 100A is combined with the electronic cigarette body 100B, the vaporization device 100A is partly accommodated in the electronic cigarette body 100B. In some embodiments, the vaporization device 100A may be referred to as a cartridge or an e-liquid storage assembly. The vaporization device 100A stores an atomization material. The atomization material may be a liquid. The atomization material may be a solution. The atomization material may alternatively be referred to as e-liquid. The e-liquid is edible. In some embodiments, the electronic cigarette body 100B may be referred to as a main body.

FIG. 2 is a schematic diagram of a demonstrative combination of an electronic cigarette 100 according to some embodiments of this application.

From the appearance, the vaporization device 100A includes a casing 1 and a base 9. The casing 1 is provided with a mouthpiece 1c which is generally flat circular. The mouthpiece 1c is located at an end portion T1 of the vaporization device 100A. In other embodiments, the mouthpiece 1c may be in other shapes.

The base 9 is located at an end portion T2 of the vaporization device 100A relative to the end portion T1. The base 9 includes a concave portion 9a used for accommodating a flavor adjusting portion 6 (may also referring to FIG. 3C). The concave portion 9a is in communication with an atomization chamber inside the vaporization device 100A. The concave portion 9a is used as an air-inlet vent, and air flows into the vaporization device 100A through the concave portion 9a. In some embodiments, the concave portion 9a is disposed at a central region of the base 9. In some embodiments, the concave portion 9a is disposed on the central axis of the vaporization device 100A, and in other words, the concave portion 9a may be located at the center position of the base 9. The flavor adjusting portion 6 stores an atomization material. In some embodiments, the vaporization device 100A may not have directivity. In some embodiments, the vaporization device 100A may be removably combined with the electronic cigarette body 100B in either of two different directions (for example, a direction in which the mouthpiece 1c shown in FIG. 2 faces upward or a direction in which the mouthpiece 1c faces downward).

The electronic cigarette body 100B has a housing 22. The housing 22 has an end portion T3. The end portion T3 is connected to the vaporization device 100A. The end portion T3 includes an opening 22h. When the vaporization device 100A is combined with the electronic cigarette body 100B, the opening 22h accommodates the end portion T2 of the vaporization device 100A. As a heated portion, the concave portion 9a receives heat from the electronic cigarette body 100B and heats the flavor adjusting portion 6 at the same time. When the flavor adjusting portion 6 is heated, the stored atomization material is heated and atomized, and the atomized gas flows into the vaporization device 100A to

provide more different flavors. A detailed structure of the vaporization device 100A is described in subsequent embodiments.

FIG. 3A, FIG. 3B, FIG. 3C, and FIG. 3D are schematic exploded views of a vaporization device 100A according to some embodiments of this application.

As shown in FIG. 3A, FIG. 3B, FIG. 3C, and FIG. 3D, in addition to the casing 1, the flavor adjusting portion 6, and the base 9, the vaporization device 100A further includes an upper cover sealing member 2, an upper cover 3, a sealing member 4, a vapor generation assembly 5, a support 61, a middle cover 71, and a sealing ring 8.

Referring to FIG. 3B, a tube 1t is provided in the casing 1. The tube 1t is in communication with an opening 1h. When the vaporization device 100A is in use, vapor generated by the vaporization device 100A may be vaped by the user through the tube 1t.

As shown in FIG. 3B, the upper cover sealing member 2 may be provided with a plurality of openings. The upper cover 3 may be provided with a plurality of openings. In some embodiments, the upper cover sealing member 2 may be provided with a first opening 2h1, a second opening 2h2, and a third opening 2h3. In some embodiments, the upper cover 3 may be provided with a first opening 3h1, a second opening 3h2, and a third opening 3h3. The first opening 2h1, the second opening 2h2, and the third opening 2h3 of the upper cover sealing member 2 are respectively corresponding to the first opening 3h1, the second opening 3h2, and the third opening 3h3 of the upper cover 3. The first opening 2h1, the second opening 2h2, and the third opening 2h3 of the upper cover sealing member 2 respectively expose the first opening 3h1, the second opening 3h2, and the third opening 3h3 of the upper cover 3.

The first opening 3h1 of the upper cover 3 may be used as part of a vapor channel. The vapor generated by the vapor generation assembly 5 may reach the tube 1t inside the casing 1 through the first opening 3h1 of the upper cover 3. The second opening 3h2 and the third opening 3h3 of the upper cover 3 may be used as part of an e-liquid channel. E-liquid stored in the vaporization device 100A may flow to the vapor generation assembly 5 through the openings 3h2 and 3h3. The E-liquid stored in the vaporization device 100A may be in contact with the vapor generation assembly 5 through the second opening 3h2 and the third opening 3h3 of the upper cover 3. The first opening 3h1 and the second opening 3h2 of the upper cover 3 are isolated from each other, and e-liquid flowing in the second opening 3h2 does not flow into the vapor channel directly. The first opening 3h1 and the third opening 3h3 of the upper cover 3 are isolated from each other, and e-liquid flowing in the third opening 3h3 of the upper cover 3 does not flow into the vapor channel directly.

In some embodiments, a quantity of the openings of the upper cover sealing member 2 may be the same as that of the upper cover 3. In some embodiments, a quantity of the openings of the upper cover sealing member 2 may be different from that of the upper cover 3. In some embodiments, a quantity of the openings of the upper cover sealing member 2 may be less than that of the upper cover 3. In some embodiments, a quantity of the openings of the upper cover sealing member 2 may be greater than that of the upper cover 3.

When some or all the members of the vaporization device 100A are combined with each other, the upper cover sealing member 2 may cover part of the upper cover 3. The upper

cover sealing member 2 may surround part of the upper cover 3. The upper cover sealing member 2 may expose part of the upper cover 3.

In some embodiments, the upper cover sealing member 2 may have elasticity. In some embodiments, the upper cover sealing member 2 may have flexibility. In some embodiments, the upper cover sealing member 2 may include silica gel. In some embodiments, the upper cover sealing member 2 may be made of silica gel.

When some or all the members of the vaporization device 100A are combined with each other, the sealing member 4 may cover part of the vapor generation assembly 5. The sealing member 4 may surround part of the vapor generation assembly 5. The sealing member 4 may expose part of the vapor generation assembly 5.

In some embodiments, the sealing member 4 may have elasticity. In some embodiments, the sealing member 4 may have flexibility. In some embodiments, the sealing member 4 may include silica gel. In some embodiments, the sealing member 4 may be made of silica gel. The sealing member 4 may have high temperature resistance. In some embodiments, the sealing member 4 has a melting point higher than 350 degrees Celsius.

As shown in FIG. 3B, the sealing member 4 has an opening 4h, and the vapor generation assembly 5 has a recess 5c. When the sealing member 4 and the vapor generation assembly 5 are combined with each other, the opening 4h of the sealing member 4 may expose at least part of the recess 5c.

As shown in FIG. 3D, the vapor generation assembly 5 includes a first electrically conductive pin 5p1 and a second electrically conductive pin 5p2. The first electrically conductive pin 5p1 and the second electrically conductive pin 5p2 are hooks curved towards two sides. Shapes of the first electrically conductive pin 5p1 and the second electrically conductive pin 5p2 have many advantages. During assembly of the vaporization device 100A, the shapes of the first electrically conductive pin 5p1 and the second electrically conductive pin 5p2 are designed to enable the first electrically conductive pin 5p1 and the second electrically conductive pin 5p2 to be easily in contact with a first electrically conductive structure 9p1 and a second electrically conductive structure 9p2. The shape design of the first electrically conductive pin 5p1 and the second electrically conductive pin 5p2 decreases a probability of poor contact between the first electrically conductive pin 5p1 and the second electrically conductive pin 5p2 and the first electrically conductive structure 9p1 and the second electrically conductive structure 9p2. The shape design of the first electrically conductive pin 5p1 and the second electrically conductive pin 5p2 further reduces steps for assembling the vaporization device 100A.

Although not drawn in FIG. 3D, the vapor generation assembly 5 may include a heating circuit disposed on a bottom surface 5s1. The heating circuit disposed on the bottom surface 5s1 is electrically connected to the first electrically conductive pin 5p1 and the second electrically conductive pin 5p2. The vaporization device 100 may increase the temperature of the vapor generation assembly 5 by providing power to the heating circuit on the bottom surface 5s1.

The support 61 may have a rectangular shape. The support 61 has a plurality of openings 61h. In some embodiments, the plurality of openings 61h are arranged on the support 61 in a matrix. In some embodiments, the support 61 may have a circular shape. In some embodiments, the support 61 may

have a triangular shape. In some embodiments, the support 61 may have a polygonal shape.

In some embodiments, the plurality of openings 61h of the support 61 are arranged at the same distance. The openings 61h of the support 61 may have the same aperture. In some embodiments, the openings 61h of the support 61 may have different apertures. In some embodiments, the opening 61h of the support 61 may have an aperture of 0.1 mm. In some embodiments, the opening 61h of the support 61 may have an aperture of 0.2 mm. In some embodiments, the opening 61h of the support 61 may have an aperture of 0.3 mm. In some embodiments, the opening 61h of the support 61 may have an aperture of 0.35 mm. In some embodiments, the opening 61h of the support 61 may have an aperture of 0.4 mm. In some embodiments, the opening 61h of the support 61 may have an aperture of 0.5 mm.

In some embodiments, the aperture of the opening 61h of the support 61 may be within a range of 0.1 mm to 0.2 mm. In some embodiments, the aperture of the opening 61h of the support 61 may be within a range of 0.2 mm to 0.3 mm. In some embodiments, the aperture of the opening 61h of the support 61 may be within a range of 0.15 mm to 0.35 mm. In some embodiments, the aperture of the opening 61h of the support 61 may be within a range of 0.3 mm to 0.4 mm. In some embodiments, the aperture of the opening 61h of the support 61 may be within a range of 0.4 mm to 0.5 mm.

The support 61 may include a plastic material. The support 61 may be made of a plastic material. The support 61 may include a metallic material. The support 61 may be made of a metallic material. In some embodiments, the support 61 may include stainless steel.

The middle cover 71 may include an opening 71h1. The support 61 may be disposed on the middle cover 71. The support 61 may be disposed above the opening 71h1 in the middle cover 71. The support 61 may cover the opening 71h1 of the middle cover 71. The length of the opening 71h1 of the middle cover 71 is approximately slightly less than the length of the support 61. The width of the opening 71h1 of the middle cover 71 is approximately slightly less than the width of the support 61. Therefore, after the support 61 is mounted in the opening 71h1 of the middle cover 71, there is no need to use an additional member for fixing the support 61 and the middle cover 71. When the support 61 is disposed on the middle cover 71, the openings 61h on the support 61 can enable an airflow to pass through.

The bottom of the base 9 includes a recess 9r1. The sealing ring 8 may be disposed inside the recess 9r1 at the bottom of the base 9. The base 9 includes openings 9h3 and 9h4 disposed at two sides of the concave portion 9a. The first electrically conductive structure 9p1 and the second electrically conductive structure 9p2 may respectively pass through the openings 9h3 and 9h4 of the base 9, and are secured on the base 9. The first electrically conductive structure 9p1 and the second electrically conductive structure 9p2 pass through the openings 9h3 and 9h4 of the base 9, and extend to an inner portion of the vaporization device 100A. The first electrically conductive structure 9p1 and the second electrically conductive structure 9p2 may have a current conduction function. The first electrically conductive structure 9p1 and the second electrically conductive structure 9p2 may provide power to the vapor generation assembly 5 inside the vaporization device 100A.

After the first electrically conductive structure 9p1 and the second electrically conductive structure 9p2 pass through the openings 9h3 and 9h4 of the base 9, an electric contact surface 9s1 of the first electrically conductive structure 9p1 and an electric contact surface 9s2 of the second electrically

conductive structure $9p2$ are exposed out of an outer surface of the base 9 . The first electrically conductive structure $9p1$ and the second electrically conductive structure $9p2$ may include metal. The first electrically conductive structure $9p1$ and the second electrically conductive structure $9p2$ may be attracted by magnetic members.

As shown in FIG. 3A to FIG. 3D, in some embodiments, the vaporization device 100 may include a protection plug $1a$. The protection plug $1a$ is detachably disposed, and extends into the opening $1h$. In this case, the protection plug $1a$ may prevent foreign matters from entering the opening $1h$. When the vaporization device $100A$ is not in use, the protection plug $1a$ may prevent an e-liquid or a condensed liquid from leaking from the opening $1h$. When the vaporization device $100A$ has just been manufactured, the protection plug $1a$ may have a good sealing effect, to prevent e-liquid from leaking during transport in the vaporization device $100A$.

Before starting to use the vaporization device $100A$, the user need to first remove the protection plug $1a$, and then use the vaporization device $100A$.

The flavor adjusting portion 6 includes a top surface $6s1$ and a bottom surface $6s2$ disposed opposite to each other. The top surface $6s1$ includes a plurality of openings $6h1$. The bottom surface $6s2$ includes a plurality of openings $6h2$. In some embodiments, the quantity of the plurality of openings $6h1$ corresponds to the quantity of the plurality of openings $6h2$. In some embodiments, the plurality of openings $6h1$ are in communication with the plurality of openings $6h2$.

As shown in FIG. 2, when some or all of the vaporization device $100A$ are combined with each other, the top surface $6s1$ of the flavor adjusting portion 6 is disposed in the concave portion $9a$ of the base 9 , and the bottom surface $6s2$ of the flavor adjusting portion 6 is exposed out of the base 9 . When some or all of the vaporization device $100A$ are combined with each other, the plurality of openings $6h2$ replace the concave portion $9a$ to be used as an air inlet vent, and air flows into the vaporization device $100A$ through the plurality of openings $6h2$.

It is to be noted that, structures of the vaporization device $100A$ shown in FIG. 3A to FIG. 3D are only examples and descriptions, and this application does not limit components to be included in the vaporization device $100A$, and also does not limit shapes of the components in the vaporization device $100A$.

FIG. 4A, FIG. 4B, FIG. 4C, and FIG. 4D respectively are a section side view, a partial enlarged side view, a section front view, and a partial enlarged front view of an electronic cigarette body $100B$ according to some embodiments of this application.

The housing 22 of the electronic cigarette body $100B$ includes a first part $T3p1$ and a second part $T3p2$ located at the end portion $T3$. The second part $T3p2$ is located between the first part $T3p1$ and the end portion $T3$. The second part $T3p2$ is configured to accommodate the end portion $T2$ of the vaporization device $100A$ and to be connected to the vaporization device $100A$.

As shown in a partial enlarged view in FIG. 4B, the first part $T3p1$ includes a base 31 . The base 31 includes a hollow structure. The hollow structure of the base 31 may be generally divided into a heating region $31a1$ and a heated region $31a2$. In some embodiments, the heating region $31a1$ and the heated region $31a2$ are arranged in a direction toward the end portion $T3$.

A heating portion 42 is provided in the heating region $31a1$. The heating portion 42 includes a hollow portion $42p$ and a heat source portion $42a$ for air to pass through. The

heat source portion $42a$ is configured to heat air in the hollow portion $42p$. In some embodiments, the hollow portion $42p$ is a through hole running through the heating portion 42 . The hollow portion $42p$ forms a first opening $42h1$ on an upper surface of the heating portion 42 . The hollow portion $42p$ forms a second opening $42h2$ on a lower surface of the heating portion 42 . The heat source portion $42a$ is provided with a heating circuit used for converting electrical energy into heat. In some embodiments, the heating portion 42 is generally a column, and the heat source portion $42a$ is disposed at a periphery of the column and around the hollow portion $42p$. However, a shape and a heating manner of the heating portion 42 is not limited in this application.

The heated region $31a2$ is provided with a heated portion 43 . The heated portion 43 includes a recess $43a$. In some embodiments, the heated portion 43 is aligned with the concave portion $9a$ of the base 9 in a depth direction of the concave portion $9a$. In this setting, when the vaporization device $100A$ is combined with the electronic cigarette body $100B$, the recess $43a$ may accommodate part of the flavor adjusting portion 6 exposed out of the base 9 . The heated portion 43 further includes an opening $43h1$ located at a bottom of the heated portion 43 . In some embodiments, the opening $43h1$ of the heated portion 43 is in communication with the first opening $42h1$ of the heating portion 42 .

Referring to FIG. 4D, an airflow channel $41p$ (identified in a dotted line in FIG. 4D) is provided in the housing 22 . In some embodiments, a width range of the airflow channel $41p$ is limited in an inner wall $22w$ of the housing 22 . In some embodiments, the airflow channel $41p$ covers the heating portion 42 of the heating region $31a1$ and the heated portion 43 of the heated region $31a2$. In some embodiments, the width of the airflow channel $41p$ is roughly equal to the width of the hollow portion $42p$. In some embodiments, the airflow channel $41p$ extends in a vertical direction, which is corresponding to an extension direction of the heating region $31a1$ and the heated region $31a2$. In some embodiments, corresponding to the airflow channel $41p$ extending in a vertical direction, an airflow direction is shown by an arrow $41f$. In this setting, along the airflow direction $41f$, the heated portion 43 in the heated region $31a2$ is located at downstream of the heating region $31a1$.

However, this application does not limit thereto. In other embodiments, the heating region $31a1$ and the heated region $31a2$ may not be arranged in the direction toward the end portion $T3$. For example, the heating region $31a1$ and the heated region $31a2$ may be arranged horizontally, or staggered in a vertical direction. Correspondingly, the airflow channel $41p$ and the airflow direction $41f$ may not extend in a vertical direction.

Referring to FIG. 4D, the first part $T3p1$ further includes an electric connection terminal 32 . In some embodiments, there are two electric connection terminals 32 . In some embodiments, two electric connection terminals 32 are disposed between the base 31 and the inner wall $22w$. When the vaporization device $100A$ is combined with the electronic cigarette body $100B$, upper ends of the two electric connection terminals 32 are in contact with the first electrically conductive structure $9p1$ and the second electrically conductive structure $9p2$ respectively, to conduct electric power to the vapor generation assembly 5 by using the first electrically conductive structure $9p1$ and the second electrically conductive structure $9p2$. In some embodiments, the electric connection terminals 32 may be combined with magnetic members. When the vaporization device $100A$ is combined with the electronic cigarette body $100B$, magnetic

attraction force between the magnetic member and the first electrically conductive structure **9p1** and between the magnetic member and the second electrically conductive structure **9p2** may prevent the vaporization device **100A** from loosing. In some embodiments, the electric connection terminals **32** include spring probes or other forms of probes to conduct electric power to the vaporization device **100A**.

The electronic cigarette body **100B** further includes a temperature sensor **44** configured to measure an air temperature. A top end of the temperature sensor **44** enters the hollow portion **42p** through the opening **42h2**. The electronic cigarette body **100B** further includes a charging member **45**, a battery **46**, and a main circuit board **47**. The charging member **45** includes a charging circuit board. When the charging member **45** is connected to an external charging cable to which a power supply is connected, the battery **46** is charged. As a power supply, the battery **46** is configured to supply electric power to electrical elements that require electricity in the electronic cigarette **100**. The main circuit board **47** is configured to control components of the electronic cigarette **100** to collaborate to implement functions of the electronic cigarette **100**. A person skilled in the art should understand that the electronic cigarette body **100B** may further include other elements to implement the functions of the electronic cigarette **100**, and only the part related to the invention spirit of this application is described in detail herein for concise.

Referring to FIG. 5 and FIG. 4A to FIG. 4D at the same time, FIG. 5 is a structural section view of an electronic cigarette **100** according to some embodiments of this application. When a user uses the electronic cigarette **100**, the suction pulls air in the electronic cigarette body **100B** to flow along the airflow channel **41p**. After flowing into the hollow portion **42p** from below the heating portion **42** through the opening **42h2**, the air is heated by heat power provided by the heat source portion **42a**, and flows into the heated portion **43** through the opening **42h1** and the opening **43h1**. In some embodiments, the heated air is about 40-60° C. Moisture in the heated air may be reduced to improve generation of condensate between the vaporization device **100A** and the electronic cigarette body **100B** and to dry generated condensate, to prevent the condensate from damaging electronic parts and components. The recess **43a** of the heated portion **43** accommodates part of a flavor adjusting portion **6**, to enable the heated air to flow into the flavor adjusting portion **6** to prompt volatilization of flavor adjusting materials in the flavor adjusting portion **6**. Air entrained with atomized gas flows into the atomization chamber of the vaporization device **100A**. In this case, the concentration and aroma of the atomized gas to be vaped by the user may be increased.

As used herein, the terms “approximately”, “basically”, “substantially”, and “about” are used to describe and consider small variations. When used in combination with an event or a situation, the terms may refer to an example in which an event or a situation occurs accurately and an example in which the event or situation occurs approximately. As used herein with respect to a given value or range, the term “about” generally means in the range of $\pm 10\%$, $\pm 5\%$, $\pm 1\%$, or $\pm 0.5\%$ of the given value or range. The range may be indicated herein as from one endpoint to another endpoint or between two endpoints. Unless otherwise specified, all ranges disclosed herein include endpoints. The term “substantially coplanar” may refer to two surfaces within a few micrometers (μm) positioned along the same plane, for example, within 10 within 1 or within 0.5 μm positioned along the same plane. When reference is

made to “substantially” the same numerical value or characteristic, the term may refer to a value within $\pm 10\%$, $\pm 5\%$, $\pm 1\%$, or $\pm 0.5\%$ of the average of the values.

As used herein, the terms “approximately”, “basically”, “substantially”, and “about” are used to describe and explain small variations. When used in combination with an event or a situation, the terms may refer to an example in which an event or a situation occurs accurately and an example in which the event or situation occurs approximately. For example, when being used in combination with a value, the term may refer to a variation range of less than or equal to $\pm 10\%$ of the value, for example, less than or equal to $\pm 5\%$, less than or equal to $\pm 4\%$, less than or equal to $\pm 3\%$, less than or equal to $\pm 2\%$, less than or equal to $\pm 1\%$, less than or equal to $\pm 0.5\%$, less than or equal to $\pm 0.1\%$, or less than or equal to $\pm 0.05\%$. For example, if a difference between two values is less than or equal to $\pm 10\%$ of an average value of the value (for example, less than or equal to $\pm 5\%$, less than or equal to $\pm 4\%$, less than or equal to $\pm 3\%$, less than or equal to $\pm 2\%$, less than or equal to $\pm 1\%$, less than or equal to $\pm 0.5\%$, less than or equal to $\pm 0.1\%$, or less than or equal to $\pm 0.05\%$), it could be considered that the two values are “substantially” or “approximately” the same. For example, being “substantially” parallel may refer to an angular variation range of less than or equal to $\pm 10^\circ$ with respect to 0° , for example, less than or equal to $\pm 5^\circ$, less than or equal to $\pm 4^\circ$, less than or equal to $\pm 3^\circ$, less than or equal to $\pm 2^\circ$, less than or equal to $\pm 1^\circ$, less than or equal to $\pm 0.5^\circ$, less than or equal to $\pm 0.1^\circ$, or less than or equal to $\pm 0.05^\circ$. For example, being “substantially” perpendicular may refer to an angular variation range of less than or equal to $\pm 10^\circ$ with respect to 90° , for example, less than or equal to $\pm 5^\circ$, less than or equal to $\pm 4^\circ$, less than or equal to $\pm 3^\circ$, less than or equal to $\pm 2^\circ$, less than or equal to $\pm 1^\circ$, less than or equal to $\pm 0.5^\circ$, less than or equal to $\pm 0.1^\circ$, or less than or equal to $\pm 0.05^\circ$.

For example, two surfaces can be deemed to be coplanar or substantially coplanar if a displacement between the two surfaces is no greater than 5 μm no greater than 2 μm no greater than 1 or no greater than 0.5 μm . A surface can be deemed to be planar or substantially planar if a displacement between any two points on the surface with respect to a plane is no greater than 5 μm no greater than 2 μm no greater than 1 μm or no greater than 0.5 μm .

As used herein, the terms “conductive”, “electrically conductive” and “electrical conductivity” refer to an ability to transport an electric current. Electrically conductive materials typically indicate those materials that exhibit little or no opposition to the flow of an electric current. One measure of electrical conductivity is Siemens per meter (S/m). Typically, an electrically conductive material is one having a conductivity greater than approximately 104 S/m, such as at least 105 S/m or at least 106 S/m. The electrical conductivity of a material can sometimes vary with temperature. Unless otherwise specified, the electrical conductivity of a material is measured at room temperature.

As used herein, singular terms “a”, “an”, and “the” may include plural referents unless the context clearly dictates otherwise. In the description of some embodiments, assemblies provided “on” or “above” another assembly may encompass a case in which a previous assembly is directly on a latter assembly (for example, in physical contact with the latter assembly), and a case in which one or more intermediate assemblies are located between the previous assembly and the latter assembly.

As used herein, for ease of description, space-related terms such as “under”, “below”, “lower portion”, “above”, “upper portion”, “lower portion”, “left side”, “right side”,

11

and the like may be used herein to describe a relationship between one member or feature and another member or feature as shown in the figures. In addition to orientation shown in the figures, space-related terms are intended to encompass different orientations of the device in use or operation. A device may be oriented in other ways (rotated 90 degrees or at other orientations), and the space-related descriptors used herein may also be used for explanation accordingly. It should be understood that when a member is "connected" or "coupled" to another member, the member may be directly connected to or coupled to another member, or an intermediate member may exist. Several embodiments of this disclosure and features of details are briefly described above. The embodiments described in this disclosure may be easily used as a basis for designing or modifying other processes and structures for realizing the same or similar objectives and/or obtaining the same or similar advantages introduced in the embodiments in the specification. Such equivalent construction does not depart from the spirit and scope of this disclosure, and various variations, replacements, and modifications can be made without departing from the spirit and scope of this disclosure.

What is claimed is:

1. An electronic cigarette, comprising:
an electronic cigarette body, and
a vaporization device,
wherein the electronic cigarette body comprises a housing
in which a power supply is provided, one end of the
housing being configured to be connected to the vapor-
ization device, wherein an airflow channel is provided
in the housing, a heating portion and a heated portion
in an airflow communication with the heating portion
being provided in the airflow channel; and
wherein one end of the vaporization device is provided
with a mouthpiece and the other end of the vaporization
device is configured to be connected to the electronic
cigarette body;
the vaporization device comprises a casing, a base, a
flavor adjusting portion for storing an atomization
material and a vapor generation assembly for gener-
ating vapor by heating e-liquid, one end of the casing is
provided with the mouthpiece, the base is located at the
other end of the casing, the vapor generation assembly
is located inside the casing, the base comprises a
concave portion, a part of flavor adjusting portion is
received in the concave portion, the other part of the
flavor adjusting portion protrudes to an outside of the
base and the casing, the flavor adjusting portion com-
prises a plurality of openings penetrating the flavor
adjusting portion, the plurality of openings is used as an
air inlet vent through which air flows into the vapor-
ization device, the other part of the flavor adjusting
portion is received in the heated portion in the elec-

12

tronic cigarette body, the heating portion is used to heat
air in the airflow channel and the heated air heated by
the heating portion flows into the flavor adjusting
portion in the heated portion to prompt volatilization of
the atomization material in the flavor adjusting portion.

2. The electronic cigarette of claim 1, wherein the concave
portion is aligned with the heated portion in a depth direction
of the concave portion.

10 3. The electronic cigarette of claim 2, wherein the concave
portion is configured to be in communication with the heated
portion of the electronic cigarette body.

15 4. The electronic cigarette of claim 3, wherein the concave
portion is located at a central region of the end portion.

5. The electronic cigarette of claim 1, wherein the heated
portion is located downstream of the heating portion in an
airflow direction.

15 6. The electronic cigarette of claim 1, further comprising
a temperature sensor, configured to measure a temperature
of the heating portion.

20 7. The electronic cigarette of claim 1, wherein the housing
has a first part and a second part located at the one end, the
second part being located between the first part and the one
end; and

25 the first part is configured to dispose the heating portion
and the heated portion, and the second part is config-
ured to be connected to the vaporization device.

30 8. The electronic cigarette of claim 7, wherein a hollow
base is provided in the first part, and a hollow part of the
hollow base comprises a heating region and a heated region,
respectively configured to dispose the heating portion and
the heated portion.

35 9. The electronic cigarette of claim 8, wherein the heating
region and the heated region are arranged in a direction
toward the one end.

10. The electronic cigarette of claim 9, wherein an electric
connection terminal is further provided in the first part, and
the electric connection terminal is disposed between the
hollow base and an inner wall of the housing.

40 11. The electronic cigarette of claim 1, wherein the vapor
generation assembly comprises a first electrically conductive
pin and a second electrically conductive pin, the base
further comprises a first opening and a second opening
45 which are disposed at two sides of the concave portion, the
vaporization device further comprises a first electrically conductive
structure and a second electrically conductive structure,
the first electrically conductive structure and the
second electrically conductive structure respectively pass
50 through the first opening and the second opening to be in
contact with the first electrically conductive pin and the
second electrically conductive pin so as to provide power to
the vapor generation assembly.
